(57) CLAIM

The ornamental design for an adjustable knee stabilizer, as shown and described.

DESCRIPTION

FIG. 1 is a perspective view of an adjustable knee stabilizer showing our new design, in use condition;

FIG. 2 is a front elevation view thereof, in open condition; FIG. 3 is a top plan view thereof, the bottom plan view being a mirror image thereof;

FIG. 4 is a right side elevation view thereof;

FIG. 5 is a left side elevation view thereof;

FIG. 6 is a rear elevation view thereof;

FIG. 7 is a perspective view of a second embodiment of the adjustable knee stabilizer showing our new design, in use condition;

FIG. 8 is a front elevation view thereof, in open condition;

FIG. 9 is a top plan view thereof, the bottom plan view being a mirror image thereof;

FIG. 10 is a right side elevation view thereof;

FIG. 11 is a left side elevation view thereof;

FIG. 12 is a rear elevation view thereof;

FIG. 13 is a perspective view of a third embodiment of the adjustable knee stabilizer showing our new design, in use condition;

FIG. 14 is a front elevation view thereof, in open condition;

FIG. 15 is a top plan view thereof, the bottom plan view being a mirror image thereof;

FIG. 16 is a right side elevation view thereof;

FIG. 17 is a left side elevation view thereof;

FIG. 18 is a rear elevation view thereof;

FIG. 19 is a perspective view of a forth embodiment of the adjustable knee stabilizer showing our new design, in use condition;

FIG. 20 is a front elevation view thereof, in open condition;

FIG. 21 is a top plan view thereof, the bottom plan view being a mirror image thereof;

FIG. 22 is a right side elevation view thereof;

FIG. 23 is a left side elevation view thereof; and,

FIG. 24 is a rear elevation view thereof.

The broken lines shown herein are for illustrative purposes only and form no part of the claimed design.
